H. J. FRANCE

TURNSTILE

Filed May 26, 1924

INVENTOR
HENRY J. FRANCE

BY
Julian H. Hunt
ATTORNEY

UNITED STATES PATENT OFFICE.

HENRY J. FRANCE, OF BROOKLYN, NEW YORK, ASSIGNOR OF ONE-HALF TO JOSEPH POPE, OF NEW YORK, N. Y.

TURNSTILE.

Application filed May 26, 1924. Serial No. 715,823.

This invention relates to improvements in turnstiles.

One of the objects of this invention is to produce a turnstile gate which will operate effectively and occupy a minimum of space, and preferably will occupy a space only slightly greater than the length of one of the arms instead of more than double the length of arms as in the conventional turnstile.

Another object of this invention is to produce a turnstile gate by which a passageway at one side of the center of rotation or axis thereof will be obstructed by one of the turnstile arms which must be rotated in order to pass, while another parallel passageway at the opposite side and adjacent to said center of rotation will be freed from the obstruction of the said rotating arms.

Another object of this invention is to produce a turnstile in which a series, and preferably four arms will be so mounted to rotate that each of such arms will successively be moved to extend in a horizontal direction to produce an effective obstruction for a passageway at one side of the axis about which it rotates and will thereafter, after movement through such passageway, be folded during its continued rotary movement at the opposite side of such center of rotation so that the space at said opposite side will be economized and another passageway free from obstruction may be positioned closely adjacent to said center, or another turnstile may be mounted to have the end of its arms extend into close proximity to said center or axis of rotation.

Another object of my invention is to produce a car vestibule in which a turnstile having foldable arms may be mounted to obstruct an ingress passageway at one side of the center of the turnstile and to free an egress passageway from the obstruction of said turnstile arms at the opposite side of the said center.

Another object of my invention is to produce a car vestibule having a turnstile guard rail extending transversely therein to divide the space into ingress and egress passageways and to provide a turnstile having its center of rotation adjacent to or within said guard rail, and means for successively extending and folding the turnstile arms to successively obstruct the ingress passageway at one side of said guard rail and to free from the normal obstruction of said arms

the egress passageway at the opposite side of said guard rail.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a fragmentary horizontal section of a car showing in plan the vestibule and adjacent floor portion with my turnstile mounted in said vestibule;

Fig. 2 is a section on the line 2—2 of Fig. 1;

Fig. 3 is a side elevation from the rear or folded side of the turnstile, the guard rail being removed;

Fig. 4 is an enlarged plan view of the turnstile proper and mechanism for operating the arms; and

Fig. 5 is a plan view of a modified form of my invention in which the cam is provided with inclined portions at opposite ends to permit operation of the turnstile in opposite directions.

Referring now to these drawings, which illustrate a preferred embodiment of my invention, T indicates my space-economizing turnstile which, in the preferred embodiment shown, is mounted in the vestibule 2 of a car 1, which vestibule is usually of quite limited space and is usually separated from the inner compartment 3 of the car by a partition or step 4.

In the said preferred embodiment shown, the vestibule is provided with the usual ingress passageway 5 and a parallel egress passageway 6 closely adjacent thereto. These passageways usually register with ingress and egress doors or doorways 5^a—6^a and are usually provided at opposite sides of a central post 7. Between and separating the passageways 5 and 6 and preferably in alignment with the post 7, I mount a relatively narrow dividing element such as the turnstile guard 8 and arrange the center of rotation 9 of my turnstile T closely adjacent to the plane of said guard 8. By the use of a turnstile having foldable arms and locating the center thereof as aforesaid, I am enabled to obstruct the passageway at one

side of the said guard 8 and to completely free from obstruction of the rotating turnstile arms the passageway 6 at the opposite side of said guard and center of rotation.

In the preferred embodiment illustrated, a turnstile post P is suitably secured to the floor intermediate the opposite ends of the guard and adjacent to one side thereof. At the upper end of said post P, I mount a rotatable element or arm carrying head 10 which, as illustrated, comprises a circular collar 11 composed of an angle iron having a horizontally extending flange 12 provided with a ball race 13 to permit the mounting of the head 10 on a flange 14 cast integrally with the post P by means of ball bearings 15. The said head 10 is, in the embodiment shown, provided with a series of four bearing brackets 16 each having pivotally mounted therein a foldable turnstile arm A. As illustrated, each of the arms A is pivoted on a pivot pin α in the brackets 16 and is caused to swing on its pivot in one direction and, as shown, to an upward, horizontally, passage-obstructing position by means of a spring 17 which is wound about the pivot pin α , has at one part an abutment against an inward extension 18 of the arm and at another part abuts against the twin members of the bracket 16. Obviously the normal action of the spring raises the arms A into the normal horizontal or passage-obstructing position. I therefore provide means for successively, during rotation, moving each of the arms A against the action of the said spring 17 to fold the same. This is accomplished when in the rotation of an arm on and by the rotatable element or arm-carrier, it has passed through the ingress passageway in extended or obstructing position and has reached the point where it would normally extend into the egress passageway. It is, of course, desirable to free said egress passage at the opposite side of the center of rotation from such arms, and, in the embodiment shown, I provide means for lowering the arms against the action of the spring. As illustrated, I provide the end of each of the inward extensions 18 of the arms A with a ball-roller 19. These ball-rollers ride when the arms are extended horizontally on the horizontally-disposed portion 20 of a cam track formed in the upper surface of a casting C. The said casting is also provided at one side with a raised or inclined cam surface 22 which, during rotation of the arm, engages its ball and, the extension 18 acting as a lever, each of the arms A as they engage the cam surface will be folded downwardly into a substantially vertical position and will be held in such vertical position until the continued rotation of the arm carrying head 10 causes the arm so acted upon to reach a radial position parallel with the ingress passageway and guard rail,

whereupon the termination of the raised cam-surface 22 will permit the arm to be raised by the spring 17 and to continue its next cycle of movement in raised or horizontally-extended position. In the preferred embodiment shown, a portion of the casting C overlies the flange 12 of the rotating member and retains the same in place on the flange 14 of the post P. As illustrated, the casting C has a core portion c 75 which fits within the hollow post P and is connected thereto by a pin 21.

In Figs. 1 to 4 I have shown a construction in which the arms are adapted to be rotated in one direction only. Obviously 80 by providing the raised cam surface 22 with an inclined portion at opposite ends, as more particularly illustrated in Fig. 5, the arms may be rotated in opposite directions. It is desirable during their rotation 85 through the ingress passageway which it is desired to obstruct, to prevent a depression of the arms and for this purpose the cover plate 23 is arranged to engage each of the balls 19 during their horizontally-extended 90 and arcuate movement through said ingress passageway.

Having described my invention, I claim:

1. A turnstile gate having a series of arms mounted to rotate about an axis, a spring 95 for raising such arms to extend horizontally during a portion of the rotary movement thereof at one side of said axis and a cam device adapted to move such arms against the pressure of the said spring for lowering such arms into substantially vertical position during that portion of rotation at the opposite side of said axis, whereby a passageway adjacent to one side of said axis may be obstructed by such arms and a passageway adjacent to the opposite side may be freed from obstruction by such arms. 100

2. The combination with a turnstile post, of a rotatable element mounted on said post, a plurality of arms pivotally mounted on and carried by said rotatable element, spring means for raising such arms to extend horizontally during a portion of the rotary movement thereof at one side of said axis and a cam device for lowering such arms against the action of the spring means into substantially vertical position at the opposite side of said axis during another portion of the cycle of rotation of the same. 115

3. The combination with a turnstile post, of a rotatable element mounted on said post, a plurality of arms carried by said rotatable element and movable from extended to folded position, and a cam device in the path of rotation of said arms adapted successively to positively fold said arms as the same are rotated on said rotatable element. 120

4. The combination with a turnstile post, of a rotatable element mounted on said post, a plurality of arms carried by said rotat- 125

able element and movable from extended to folded position, a cam device in the path of rotation of said arms comprising a horizontal cam track portion, an inclined portion and a vertical portion, and means on each of such arms adapted during the rotation thereof to engage said cam device to cause the said arms to be folded.

5. The combination with a turnstile post, 10 of a rotatable element mounted on said post, a plurality of arms pivotally mounted on and carried by said rotatable element and movable from extended to folded position, a

spring for moving the arms in one direction to one of such positions, a cam device 15 having a horizontal portion, an inclined portion and a vertical portion, and means on each of such arms adapted during the rotation thereof to engage said cam device to cause the same to be moved into the opposite position against the action of said spring.

In witness whereof, I have signed my name to the foregoing specification.

HENRY J. FRANCE.
